United States Patent Office.

J. H. L. TUCK, OF OTTAWA, ILLINOIS.

Letters Patent No. 99,501, dated February 1, 1870.

IMPROVEMENT IN CORN-HARVESTER.

The Schedule referred to in these Letters Patent and making part of the same.

To all whom it may concern:

Be it known that I, J. H. L. TUCK, of Ottawa, in the county of La Salle, in the State of Illinois, have invented a new and improved Machine for Cutting and Shocking Corn-Stalks in the Field; and I do hereby declare that the following is a full, clear, and exact description of the construction and operation of the same, reference being had to the annexed drawings, in which—

Figure 1 is a horizontal plan,

Figure 2, a vertical plan, and

Figure 3, a sectional view of the cutter.

This invention relates to a machine by means of which raisers of stock can cut and bind their corn-stalks in shocks in the field, thus making it available for cattle-fodder during winter. This operation is performed with my machine in a very expeditious manner, and with less expense for hand-labor than is done by other machines devised for this purpose.

I construct a platform, A, the forward part of which is hung on the wheels B and B', the wheel B being a driving-wheel, and may have corrugations or teeth on its circumference, in order to catch in the ground.

To the hub of the wheel B is attached a cog-wheel, C, which meshes into the pinion C', on shaft D. On this same shaft is placed the bevel-wheel E, meshing into the bevel-wheel E', on shaft F.

At the lower end of this shaft F, is adapted the double-grooved pulley G, from which a rope or twisted belt, g, communicates motion to the cutter H.

Over this cutter H is built a small platform, I, terminating forward in the shape of a fork, one side of which forms a knife-edge, h, or a cutting-edge may be fastened thereto, so that the cutter H, in revolving, will form a shear with each of its four blades as they come in rotation against the sharp edge h.

On the platform I are constructed a double set of carrying-belts, J J J J, into which spikes K K K are inserted.

These belts J J J J receive their motion through a rope or twisted belt from the double-grooved pulley G, which drives one of the upright shafts L L L L.

To the lower end of this shaft, and under the platform I, is fastened a cog-wheel, M, which meshes into another cog-wheel of the same size on the next upright shaft.

Back of the carrying-belts J J J J, and at the rear end of the platform A, is constructed a railing fence, N, having in it a gate, N', swinging open backward.

Forward of the machine, and over the axle-tree, is an apparatus for twisting ropes of straw or hay. It is

composed of the box O, the revolving clamp P, and the pressure-foot Q.

The revolving clamp P has on it a grooved pulley, R, from which a belt passes on to a similar pulley on shaft D.

A caster-wheel or roller, U, is adapted, under the rear part of the platform A, to support its weight, and that of the corn-stalks.

To operate the machine, it is drawn over a corn-field by a team of horses, in a manner similar to a reaping-machine, the machine cutting a single row of corn-stalks at each passage; and the stalks, as fast as they are cut, are seized by the carrying-belts J J J J, which carry them in an upright position backward, and finally deposit them against the railing N. This is continued until the operator judges the quantity sufficient to form a "shock," when he stops the machine, and, by means of a straw rope, which has been previously laid on hooks along the railing N, he ties all the stalks on the platform A into a bundle or shock; then he opens the gate N', and passing a rope, S, which is fastened on the platform A, forward of the bundle or shock, thence around backward through the gate N', he pulls the bundle out through the gate, and deposits it on the ground upright, and in a condition which requires no more attention until actually needed for fodder.

My machine differs from other machines devised for cutting corn-stalks, in this, that after the passing of the machine over the ground, and with only two attendants, the stalks are cut, tied in a shock, and placed on the ground upright, requiring no further attention, a result which has not been obtained with any machine hitherto known; and also by having combined with it a rope-spinning apparatus.

What I claim as new in my invention, and desire to secure by Letters Patent is—

1. The combination of the revolving cutter H, horizontal carrying-belts J, railing N, gate N', platform I, discharge-rope S, bevel-gear E and E', cords or bands g, upright shafts L and L, and the main platform A, arranged, operating, and constructed as and for the purposes set forth.

2. The rope-spinning apparatus, composed of the box O, the revolving clamp P, and the pressure-foot Q, when forming part of a machine for cutting corn-stalks in the field, substantially as described.

J. H. L. TUCK.
